HANGERS FOR LIGHTING FIXTURES

Michael Henry Kruger, Malden, Mass., assignor to A. L. Smith Iron Company, Chelsea, Mass., a corporation of Massachusetts

Application January 26, 1951, Serial No. 208,065

4 Claims. (Cl. 248—343)

This invention relates to lighting fixtures in general, and more especially to hangers, such as disclosed in the co-pending application for Patent Ser. No. 32,333, of which the present is a divisional application.

It is an object of the present invention to provide an improved hanger including an inverted dome-shaped disk, means for securing the same to the upper ends of curved downwardly extending supporting stems for connecting the disk to the upper wall of a lighting fixture.

These and other features, capabilities and advantages of the invention will appear from the subjoined detailed description of a specific embodiment thereof illustrated in the accompanying drawings, in which

Fig. 1 is a perspective of one embodiment.

Fig. 2 is an enlarged fragmental view partly in section of a hanger.

Fig. 3 is a section on the line 3—3 of Fig. 2.

In the embodiment shown there is illustrated a lighting fixture 1 having a casing 2 extending from the upper face thereof to receive a ballast housing, not shown. The casing 2, see particularly Figs. 2 and 3, has an upper wall 3 which is provided with openings to receive the bushings 4 which may be secured to the ends of the stems 5. The bushings 4 in turn may be anchored and secured in place to the upper wall 3 by the screw threaded nuts 6.

The upper ends of the stems 5, in the present instance, are indented at 7 adjacent their upper circular heads 8 to be wider in one direction than the normal diameter of the stems 5 and narrower than the normal diameter of the stems in a direction at right angles to said one direction so that after the heads 8 have been passed through the enlarged recess portions 9, the neck or indented portions 7 may slide up into the diminished recess portions 10 of the strap 11 secured in the dome-shaped canopy 12 and anchored against turning and displacement. The strap 11 is connected by any suitable means, such as the bushing 13 and nut 14, to the lower end of the conduit or the like fixed in the ceiling, and the canopy 12 in turn is connected to the lower end of the bushing 13 by any suitable means, such for instance as the screw 15, extending up through the canopy 12 into the cap 16, screw threadedly connected to the lower end of the bushing 13. The strap 11 as clearly shown in Fig. 2 has its enlarged recess portions 9 in the two downwardly and outwardly flaring depending portions of the strap 11 with the diminished recess portions 10 in the upwardly and outwardly flaring portions of the strap 11 and only the diminished recess portions 10 registering with the recesses in the canopy 12.

Obviously the canopy 12, although illustrated as a dome-shaped disk may assume other conformations, and the stems 5 which are curved or arcuate may assume other conformations, even straight, and the stems 5 may be connected to the casing 2 by means other than the bushings 4, without departing from the general spirit of the invention.

It is obvious that various changes and modifications may be made to the details of construction without de-

2

parting from the general spirit of the invention as set forth in the appended claims.

I claim:

1. A hanger for a lighting fixture including hanger stems adapted to be connected at their lower ends to the lighting fixture, a canopy, a strap in said canopy, and means for independently connecting said canopy and strap to a ceiling, there being radially extending slots in said canopy extending to the edge thereof, said strap having two portions extending downwardly and outwardly in opposite directions and then continuing upwardly and outwardly, there being openings in said strap each having an inner enlarged part in said downwardly and outwardly extending portions and an outer diminished part in said upwardly and outwardly extending portions, the diminished parts of the openings in said strap registering with the slots in said canopy, the upper ends of each of said stems having indented neck portions wider in one direction than the normal diameter of the stem and narrower than the normal diameter of the stem in a direction at right angles to said one direction and outer plain head portions, the outer head portions during assembly passing through the enlarged parts of said openings and then coming to rest above said strap with the flat neck portions registering with the diminished parts of said openings, the canopy anchoring the stems both against turning and displacement in the upwardly and outwardly flaring portions of the strap.

2. A hanger for a lighting fixture including arcuate hanger stems adapted to be connected at their lower ends to the lighting fixture, a dome-shaped canopy disk, a strap in said disk, and means for independently connecting said disk and strap to a ceiling, there being radially extending slots in said disk extending to the outer edge of the disk at the outer ends of the slots and spaced from one another at the inner ends of the slots, said strap having two portions extending downwardly and outwardly in opposite directions and then continuing upwardly and outwardly, there being openings in said strap each having an inner enlarged part in said downwardly and outwardly extending portions and an outer diminished part in said upwardly and outwardly extending portions, the diminished parts of the openings in said strap registering with the slots in said disk, the upper ends of said stems having indented neck portions wider in one direction than the normal diameter of the stem and narrower than the normal diameter of the stem in a direction at right angles to said one direction and outer plain head portions being larger than the width of the slots and the width of the diminished parts of said openings and, the outer head portions during assembly passing through the enlarged parts of said openings and then coming to rest above said strap with the flat neck portions registering with the diminished parts of said openings and the indented neck portions during assembly entering said slots at the outer edge of the disk, the disk anchoring the stems both against turning and displacement in said upwardly and outwardly flaring portions of the strap.

3. A hanger for a lighting fixture having arcuate hanger stems adapted to be connected at their lower ends to a lighting fixture, a dome-shaped canopy disk, a strap in said disk, and means for independently connecting said disk and strap to a ceiling, there being radially extending slots in said disk extending to the outer edge of the disk and wholly lying in the portion of the wall of the disk flaring outwardly away from the horizontal, said strap having two portions extending downwardly and outwardly in opposite directions and then continuing upwardly and outwardly there being openings in said strap each having an inner enlarged part in said downwardly and outwardly extending portions and an outer diminished part in said upwardly and outwardly extending portions, the outer

diminished parts of said openings in said strap alone registering with the slots in said disk, the upper ends of said stems having indented neck portions wider in one direction than the normal diameter of the stem and the width of the diminished parts of said openings but narrower than the enlarged parts of said openings and narrower than the width of the diminished parts of said openings and normal diameter of the stem in a direction at right angles to said one direction and outer plain head portions, the outer head portions being larger than the width of the slots and the width of the diminished parts of said openings and during assembly passing through the enlarged parts of said openings and then coming to rest above said strap with the flat neck portions registering with the diminished parts of said openings and the indented neck portions during assembly entering said slots at the outer edge of the disk, the disk anchoring the stems both against turning and displacement in said upwardly and outwardly flaring portions of the strap.

4. A hanger for a lighting fixture including hanger stems adapted to be connected at their lower ends to the lighting fixture, a canopy, a strap in said canopy, and means for independently connecting said canopy and strap to a ceiling, there being radially extending slots in said canopy extending to the edge thereof, said strap having two portions extending downwardly and outwardly in opposite directions and then continuing upwardly and outwardly, there being openings in said strap each having an inner enlarged part in said downwardly and outwardly

extending portions and an outer diminished part in said upwardly and outwardly extending portions, the diminished parts of the openings in said strap registering with the slots in said canopy, the upper ends of each of said stems having indented neck portions wider in one direction than the normal diameter of the stem and narrower than the normal diameter of the stem in a direction at right angles to said one direction and outer plain head portions, the outer head portions during assembly passing through the enlarged parts of said openings and then coming to rest above said strap with the flat neck portions registering with and extending through the diminished parts of said openings and the slots in said canopy when the canopy anchors the stems both against turning and displacement in the upwardly and outwardly flaring portions of the strap.
